UNITED STATES PATENT OFFICE.

GEORGE W. SHIEBLER, OF NEW YORK, N. Y.

DESIGN FOR A HANDLE FOR SPOONS, &c.

SPECIFICATION forming part of Design No. 30,874, dated May 30, 1899.

Application filed May 8, 1899. Serial No. 716,028. Term of patent 7 years.

To all whom it may concern:

Be it known that I, GEORGE W. SHIEBLER, a citizen of the United States, residing at New York, in the borough of Brooklyn, Kings county, State of New York, have invented and produced a new and original Design for the Handles of Spoons and Similar Articles, of which the following is a specification, reference being had to the accompanying drawings, forming part thereof, in which—

Figure 1 is a plan of the obverse side of the handle, and Fig. 2 a plan of the reverse side.

The leading features of my design consist in the surface ornamental lines that are substantially parallel with the edges of the handle and are provided with leaflet ornaments at intervals, as shown.

The ornamental design of the obverse of the handle comprises the substantially paral-

lel surface lines *a*, extending along the edges 20 of the handle, the leaflet ornaments *b*, disposed at intervals along the handle, the scroll-leaflet group *c*, and trefoil ornaments *d*.

The ornamental design of the reverse of the handle comprises the substantially parallel 25 surface lines *a'*, extending along the edges of the handle, the scroll-leaflet ornament *b'* at the base of the handle, the trefoil ornaments *d'*, and leaflets *c'*.

What I claim is—

The design for the handle of a spoon or similar article, substantially as shown and described.

Signed by me this 6th day of May, 1899.
GEO. W. SHIEBLER.
